E. KOERNER

DRYING APPARATUS FOR TOBACCO AND THE LIKE

Filed August 3, 1925

FIG. 1.

FIG. 2.

FIG. 3.

22 Inventor:

Ewald Koerner

UNITED STATES PATENT OFFICE.

EWALD KOERNER, OF DRESDEN, GERMANY.

DRYING APPARATUS FOR TOBACCO AND THE LIKE.

Application filed August 3, 1925. Serial No. 47,841.

To all whom it may concern:

Be it known that I, EWALD KOERNER, a citizen of the German Republic, residing at Dresden, Germany, have invented certain new and useful Improvements in Drying Apparatus for Tobacco and the like (for which I have filed application in Germany April 16, 1924), of which the following is a specification.

This invention relates to an apparatus for drying tobacco and the like and of the kind in which the materials are fed into a revolving drum enclosed in a jacket containing a heating element, and the invention consists in the provision of a fire box arranged inside of the jacket so that it can travel from one end of the drum to the other. The invention also includes a suitable mechanism whereby the fire box is kept automatically in motion. This arrangement has, as compared with the old arrangements with one or more fixed fire boxes, the advantage that the drum will be uniformly heated throughout its length by means of a single fire box which can easily be attended to.

Fig. 1 of the accompanying drawings represents a side view of the apparatus, partly in section,

Fig. 2, an end view, and

Fig. 3, a cross-section of the same.

The drying drum 3 is enclosed in a jacket 1 and is supported by means of rollers 23 on the end members 2 of the jacket so that it can be kept in rotary motion. A belt drive 16 operates, by means of a pinion 9, a toothed ring 8 on the drum so as to rotate the latter. The materials, for instance tobacco or the like, are fed into one end 40 of the drum from a hopper 4, and discharged at the other end through a hood 5 which embraces the end of the drum and leads off the vapours through a discharge pipe 7.

A fire box 11, fitted with an ash receptacle 22, is arranged in the box 1 under the drum 3. This fire box is fitted with rollers 6 whereby it is supported on track rails

10 so that it can travel from one end of the drum 3 to the other. One or more endless chains 13, which are guided over sprocket wheels 12 at opposite ends of the apparatus, are connected to the fire box so that they can be used for moving the latter along the track. For this purpose one set of sprocket wheels is mounted on a shaft fitted with a worm wheel 17 which is driven by a worm 18. A belt gearing 19 of known type, comprising one open and one crossed belt, one loose and two fast pulleys, is used for driving the worm 18, and a belt shifter 21 is provided whereby either belt may be put into operation for driving the worm and for moving the fire box. The belt shifter is controlled by a double-armed lever which is operated, for reversing the movement of the fire box at the end of each stroke, by stops 20 connected to different stretches of one of the chains 13.

The jacket 1 is fitted with a fire door 70 14 through which, when the fire box coincides with the same, the fire can be stoked. The products of combustion are discharged from the jacket through pipes 15.

I claim:

1. An apparatus for drying tobacco and the like, comprising a rotatable drum, a stationary jacket enclosing said drum, a fire box arranged in the jacket under the drum so that it can be moved longitudinally of the latter, and means for keeping said fire box automatically in motion from one end of the drum to the other.

2. A conveying device for use in an apparatus according to claim 1, comprising an endless travelling chain to which the fire box is connected, a worm gear for driving the chain, a reversing belt gear for operating said worm gear, a belt shifter for said belt gear, a lever controlling said belt shifter, and stops connected to the chain so as to operate said lever for reversing the movement at each end position of the fire box.

EWALD KOERNER.
